UNITED STATES PATENT OFFICE.

CARL THEODOR REMUS, OF DRESDEN, SAXONY, GERMANY. ASSIGNOR TO
JEAN SCHERBEL, OF SAME PLACE.

DIE FOR MAKING PAPER BOXES.

SPECIFICATION forming part of Letters Patent No. 329,080, dated October 27, 1885.

Application filed June 12, 1885. Serial No. 168,446. (No model.) Patented in England May 19, 1885, No. 6,153, and in Germany July 15, 1884, No. 30,982.

To all whom it may concern:

Be it known that I, CARL THEODOR REMUS, a subject of the Emperor of Russia, residing at the city of Dresden, in the Kingdom of Saxony, 5 Germany, have invented certain new and useful Improvements in Dies for Making Paper Boxes, of which the following is a specification.

This invention relates to dies for making paper boxes in which the body and cover are 10 made of seamless bodies of considerable height; and the invention consists of a female die having a radially-grooved top surface, a ring-shaped holder having a grooved under side, and a male die having a ribbed lower part and 15 a smooth upper part.

In the accompanying drawings, Figure 1 represents a vertical central section of a paper box made by my improved dies. Figs. 2 and 3 are vertical central sections of two different 20 sets of dies for making seamless covers and bodies for paper boxes. Figs. 4 and 6 are bottom views of the holders for the card-board, and Fig. 5 is a diagram showing the position of the grooved holder to the grooved top surface of the female die. 25

Similar letters of reference indicate corresponding parts.

e in the drawings represents the male die, which is made either of round, square, or oblong shape, according to the shape of the box 30 that is desired to be produced. The male die *e* is provided at the lower part with ribs in the nature of saw-teeth, which ribs extend in round dies around the same, while in square 35 or oblong dies they are arranged at the rounded-off corners of the same.

a is the female die, which is provided at its top surface with radial grooves *a'*, as shown in Figs. 2 and 3. On the female die *a* rests a 40 ring-shaped holder, *d*, that is grooved at the under side, the grooves *d'* extending in round holders around the same, as shown in Fig. 4, while in oblong forms of holders the radial 45 grooves are arranged only at the corners, as shown in Fig. 6. The relative position of the holder to the grooved top surface of the female die *a* is shown in Fig. 5, and is such that the raised portions of the grooved parts are adjacent to and vertically above each other.

The card-board interposed between the female die *a* and the holder *d* is guided by the raised portions of said parts, whereby the friction of the board with these parts is diminished when the board is drawn into the female die *a* by the descent of the male die *e*. The 50 grooves *a'* and *d'* also prevent any lateral shifting of the card-board, so that only folds of uniform size and at regular distance from each other are formed, as the card-board can be drawn in to a considerably greater depth than 55 heretofore. Paper boxes with seamless bodies of considerably greater depth can thus be made which could not be produced with the smooth dies and holders heretofore in use.

In oblong boxes with rounded-off corners 60 the dies are provided with radial grooves at the corners, the grooves being extended to some distance at both sides of the corners and made to diverge slightly, as shown in Fig. 6. By this arrangement of the grooves the crowding of the card-board at the upper higher parts 65 of the rounded-off body or cover is prevented, and the stock crowded somewhat from the arc-shaped corners toward the smooth parts of the 70 box-sections. When the card-board, which is 75 held between the female die and the holder, is acted upon by the male die, it is drawn into the female die and successively taken hold of by the teeth of the male die, whereby the bottom 80 of the box-section is relieved from the strain, the tearing of the bottom owing to a too great 85 strain exerted thereon by dies is prevented, and thereby a main objection to making box-sections of great height from card-board overcome. Another objection to the successful drawing of such box-sections consists in the formation of uneven folds or in the irregular 90 crowding of the folds, whereby defective boxes are obtained, which latter objection is remedied by the grooved top surface of the female 95 die and the grooved holder.

The female die is made of extra depth, so that the card-board from which the box-section is made is drawn down in the female die for a considerable distance after it has been 95 shaped until it arrives at the bottom of the die. The downward motion of the card-board into the female die *a* by the male die serves not

only to press the box-section into shape, but also to polish the outer surface of the same, so as to impart a finished appearance to the box-section.

- 5 The edges of the box-sections are re-enforced by sheet-metal rims, which are lapped over and clamped to the edges, so that a paper box with seamless sections of considerable strength is obtained.
- 10 Having thus described my invention, I claim as new and desire to secure by Letters Patent—
1. The combination of a female die having a grooved top surface, a ring-shaped holder having a grooved under side, and a ribbed male die, substantially as set forth.
  - 15 2. The combination of a female die having

20 a grooved top surface, a card-board holder having a grooved under side, and a male die having a ribbed lower part and a smooth upper part fitted into the female die, whereby the card-board is drawn down into the female die and pressed into shape and polished at the outer surface by friction, substantially as set forth.

25 In testimony whereof I have signed my name to this specification in the presence of two subscribing witnesses.

CARL THEODOR REMUS.
